UNITED STATES PATENT OFFICE.

HEINRICH UJHELY, OF VIENNA, AUSTRIA-HUNGARY.

PROCESS OF DECOLORIZING AND DEODORIZING HEAVY MINERAL OILS.

SPECIFICATION forming part of Letters Patent No. 289,788, dated December 4, 1883.

Application filed February 24, 1883. (No specimens.)

To all whom it may concern:

Be it known that I, HEINRICH UJHELY, a subject of Austria-Hungary, residing at Vienna, in the Province of Nether Austria, in the Empire of Austria-Hungary, have invented certain new and useful Improvements in Process of Decolorizing and Deodorizing Heavy Mineral Oils; and I do hereby declare the following to be a full, clear, and exact description of the invention, such as will enable others skilled in the art to which it appertains to make and use the same.

My invention relates to an improved process of decolorizing and deodorizing heavy mineral oils. I call "heavy mineral oils" such oils the specific gravity of which is equal to or exceeds .7, no matter what source they are derived from.

In order to decolorize and deodorize any heavy mineral oil it is first dissolved in any light hydrocarbon, the boiling-point of which is below or at least not much above 100° Celsius. The quantity of light hydrocarbon should be preferably larger than necessary for thoroughly dissolving the heavy oil. This solution is boiled with a suitable quantity of the insoluble residuum obtained in the manufacture of ferro-cyanide of potassium, which residuum is known as "blackening" or "blacking," (German "schwärze"); and it consists essentially of animal charcoal with traces of iron, sulphuret of iron, silicates of potassium, and sodium, &c., or with a mixture of these said animal charcoals. No accurate proportion can be given as to the quantity of the said carbonaceous substances to be added to the hydrocarbon solution, as this proportion must be varied in

accordance with the quantity of impurities contained in the mineral oil. This boiling may be effected under pressure or by employing a cooler by which the evaporated parts of the oil are condensed and again conducted into the boiling-vessel, or by means of any other apparatus which permits the boiling of a certain quantity of volatile liquids without diminishing them by evaporation. The solution, which by this process has been decolored, is now separated from the charcoal by filtration, and finally submitted to distillation in order to separate from the heavy mineral oil or oils the light hydrocarbons which have been employed as solvents. The said process of distillation is carried on to that point only until all light hydrocarbons are evaporated, after which the heavy mineral oils remain in the distilling-vessel in a perfectly colorless and odorless state.

What I claim is—

The process of decolorizing and deodorizing heavy mineral oils, which consists in dissolving them in light hydrocarbon oils, adding to the solution the insoluble residuum obtained in the manufacture of ferro-cyanide of potassium, as described, boiling the mixture, filtering the same, and finally distilling from the filtrate the hydrocarbon solvent, all substantially as set forth.

In testimony whereof I affix my signature in presence of two witnesses.

HEINRICH UJHELY.

Witnesses:

WILLIAM HUNING,
JAMES RILEY WEAVER.
